UNITED STATES PATENT OFFICE.

JOSEPH R. SMITH, OF WATERBURY, CONNECTICUT, ASSIGNOR TO WATERBURY BUTTON COMPANY, OF WATERBURY, CONNECTICUT, A CORPORATION OF CONNECTICUT.

DESIGN FOR A BUCKLE.

40,697.

Specification for Design.

Patented May 17, 1910.

Application filed March 3, 1910. Serial No. 547,166. Term of patent 14 years.

To all whom it may concern:

Be it known that I, JOSEPH R. SMITH, a citizen of the United States, residing at Waterbury, county of New Haven, State of Connecticut, have invented a new, original, and ornamental Design for Buckles, the same being shown in the accompanying drawing, in which—

Figure 1 is a front elevation and Fig. 2 is an edge view of said buckle.

I claim—

The ornamental design for a buckle, as shown.

JOSEPH R. SMITH.
